STERILIZING APPARATUS

Karl W. Kornopp, Winnetka, Ill.

Application October 31, 1932, Serial No. 640,407

2 Claims. (Cl. 99—18)

The present invention relates to sterilizing apparatuses or the like.

Among the objects of the present invention is to provide a novel sterilizing apparatus or device adapted to efficiently sterilize bottles or other similar and like receptacles, or the contents thereof, whereby the same may be easily and readily placed therein and removed therefrom.

Another object of the present invention is to provide a novel sterilizing apparatus or the like in which suitable means is provided for supporting a plurality of receptacles or the like whereby the sterilizing medium may have substantially unrestricted movement throughout the apparatus and around these receptacles for efficient operation.

The present invention contemplates the idea of providing a novel sterilizing apparatus wherein a suitable receptacle supporting means is mounted for rotation, suitable means being provided for holding these receptacles or the like against radial displacement therein.

Still another object of the present invention is to provide a novel sterilizing apparatus or the like in which suitable means is provided for supporting a plurality of series of radially disposed receptacles or the like in spaced relation circumferentially.

Still a further object of the present invention is to provide a novel sterilizing apparatus or the like in which suitable means is provided for supporting a plurality of series of radially disposed receptacles or the like in spaced relation circumferentially, and in which the receptacles of the series are disposed in contiguous relation longitudinally of the supporting means.

The present invention also includes as an object the idea of providing a novel supporting means for receptacles or the like in a sterilizing apparatus, which includes spaced frame members between which extends a plurality of circumferentially spaced members for holding a plurality of rows of receptacles or the like, suitable means being provided for preventing displacement of these rows of receptacles.

Another object within the purview of the present invention is to provide a novel receptacle supporting means for a sterilizing apparatus or the like which comprises or includes spaced frame members between which extend inner and outer rows of members in spaced relation for receiving a plurality of receptacles or the like, these members engaging the receptacles in spaced relation, suitable means being further provided for preventing displacement of said rows of receptacles.

More specifically, the present invention includes the idea of disposing the members of these rows in radial alignment and providing releasable means for each of the rows of receptacles for holding the same in place, such means being easily and readily operated whereby the receptacles may be removed and replaced.

Other objects, features, capabilities and advantages are comprehended by the invention, as will later appear and as are inherently possessed thereby.

Referring to the drawings:

Figure 1 is a view in side elevation of a device made in accordance with the present invention, with parts broken away to disclose the construction thereof more in detail;

Figure 2 is a view in end elevation of the embodiment shown in Figure 1 of the drawings, with parts broken away to more clearly disclose the construction thereof;

Figure 3 is a fragmentary view in cross section of retaining means for the receptacles or the like;

Figure 4 is a view in cross-section taken in the plane represented by line 4—4 of Figure 3 of the drawings;

Figure 5 is a fragmentary view partly in plan and partly in cross-section taken in the plane represented by line 5—5 of Figure 2 of the drawings.

Referring now more in detail to the drawings, an embodiment selected to illustrate the present invention is disclosed as comprising an outer casing 2 within which is mounted a receptacle supporting means 4 for supporting a plurality of bottles or other receptacles 6, it of course being understood that these bottles may be filled with a fluid or other medium to be sterilized, or the same may be empty and placed therein for sterilizing purposes. In the present invention, these receptacles are bottles filled with fluid to be sterilized, and the same are sealed as by means of a cap fitting over the open end thereof.

The outer casing 2 comprises a substantially cylindrical shell 8 closed at the ends thereof as 45 by means of the end plates 10 and 12 which are secured thereto in any desired manner to form a fluid tight joint. This outer casing may be mounted upon a suitable support 14, as shown, which in turn may be secured to a floor or other 50 foundation.

The bottle or receptacle supporting means comprises a power-driven shaft 16 extending longitudinally of the casing 2, and being mounted adjacent its ends in the bearings 18 and 20 pro-

vided on the end plates or heads 10 and 12, respectively. The bearing 20 is secured to the inner face of the end 12, while the bearing 18 extends through the plate 10 and is made fluid tight as 5 by means of an adjustable gland 22, the shaft 16 extending outwardly beyond the plate 10 and being provided with a sprocket 24 driven by the sprocket chain 26 by means of a motor 28. In the embodiment disclosed, the motor 28 drives a gear 10 reducer 30 through the medium of a belt 32, the reducer in turn driving the sprocket chain 26 through the sprocket wheel 34.

Mounted for rotation with the shaft 16 and disposed within the casing 2 is a frame, generally referred to as 36, for holding a plurality of bottles or receptacles 6. This frame comprises oppositely disposed frame members 38 and 40 disposed adjacent the bearings 18 and 20, respectively, and which are connected together and 15 reinforced by a plurality of members 41 extending therebetween and rigidly secured thereto in any desired manner. Extending between the frame members 38 and 40 is an inner circular row of receptacle holding members 42, these 20 members 42 being spaced circumferentially, as disclosed. An outer circular row of receptacle holding members 44 is provided, and the same extends between the frame members 38 and 40 25 in a manner similar to the members 42. These members 44 of the outer row are spaced as disclosed, and are in substantially radial alignment with members 42 of the inner row, thus providing a plurality of longitudinally disposed compartments for receiving a plurality of series of rows of 30 receptacles.

As clearly disclosed in the present embodiment, spaced adjacent members 42 engage the neck portion of the receptacles or bottles 6 adjacent an end thereof, while adjacent members 44 engage the widened body portion of these receptacles or bottles adjacent their opposite end. It will be 40 clearly apparent that because of the radial disposition of these members 42 and 44, the bottles or receptacles are effectively held against displacement and the sterilizing medium is permitted to properly circulate within the casing 2.

As clearly shown in Figure 1 of the drawings, the members 42 and 44 extend through suitable aligned apertures in the plates 38 and 40 and are 50 maintained in position as by means of the pins 46. These rods or receptacle holding members 42 and 44 may be suitably covered with rubber, rubber composition, or other similar material 48, which likewise serves as a suitable medium for the wedging of the bottles between adjacent members 42 and 44. In order, however, to positively maintain each series or row of receptacles in its proper position, suitable means is provided to prevent its radial displacement. Such means as 55 disclosed comprises a plurality of retaining members or plates 50 each disposed in opposite relation to the outer end of the receptacles of each series which is adapted to prevent the outward and radial movement of the bottles. Each of these plates or retaining members 50 extends between the frame members 38 and 40 and is provided with tubular portions 52 and 54 adjacent each end, rivets 56 passing through aligned openings in the frame members 38 and 40 and tubes 52 60 and 54, respectively, for pivotally mounting the plate or retaining member 50 thereto, these rivets being maintained in their proper position as by means of a cotter or other similar locking member 58. In order to hold the plates or retaining members 50 in the position as shown in Figure 2

of the drawings, each of the same is provided with a substantially tubular housing 60, within which is disposed a plunger 62 normally urged into its extended position as by means of a coil spring 64. Outward movement of the plunger 62 is limited by means of a lug or pin 66 movable within a slot 68 formed in the tubular portion 60 and extending outwardly therebeyond. The end of the plunger 62, when the plate is in the position as shown in Figure 2 of the drawings, is received in an opening 70 for releasably locking the retaining member or plate 50 in position to prevent outward and radial displacement of the receptacles of a series.

The outer casing 2 is formed with an opening 15 72 normally closed by a closure member 74, suitably hinged as at 75, whereby sterilized receptacles or the like may be removed from the receptacle supporting means 36, and other receptacles or the like to be sterilized may be introduced and placed in position therein. The closure member 74 is held in fluid-tight association with the casing 2 by means of locking bars 76, each of which is formed with bifurcated end portions 78 and 80 engaged by the nuts 82 and 84 20 threaded on the end of eye members 86 and 88 pivoted to the outer shell 8 of the casing 2. As clearly disclosed in Figures 2 and 5 of the drawings, the eye member 88 is pivotally mounted upon the pin or bolt 90 forming the hinged member 30 for the cover 74.

As clearly disclosed in the drawings, the sterilizing medium, as for example, steam or the like, may be introduced into the casing 2 through the pipe connection 92, a drain pipe 94 being provided 35 for disposing of the condensate therefrom. In accordance with usual practice, this steam is introduced at about 240° F. for a given length of time, the circulating steam passing out of the casing 2 through the exhaust conduit 93, the flow 40 therein being regulated by the valve 95. The pressure in the device is normally determined by a steam pressure gauge 96 and the excess pressure in the casing 2 is exhausted through the safety valve 98. The temperature in the apparatus may be determined by means of a thermometer 100. After the steam or other sterilizing 45 medium has circulated in the casing for a sufficient length of time, the same is shut off and hot water introduced through the conduit 92. The water gradually rises in the casing 2 and the 50 overflow passes out through the outlet conduit 102 controlled by valve 104. The temperature of the water introduced is gradually lowered until the receptacles and the contents thereof are sufficiently cool so they can be handled.

In operation, the receptacle holding means 36 supporting a plurality of receptacles to be sterilized, is rotated through the medium of the motor 28 in a sterilizing medium which may be introduced through the inlet 92. When the receptacle or the contents thereof have been suitably sterilized, the cover or closure member 74 may be unlocked and the same moved to a position whereby access to the receptacles 6 may be gained. The receptacles adjacent the opening 72 may then be removed and replaced by other receptacles to be sterilized and the supporting means 36 rotated sufficiently to move other rows or series of receptacles into a position opposite the opening 72. 65 These receptacles in turn may then be removed and replaced by still further receptacles to be sterilized, and this process repeated until there 70 has been a complete change of bottles or receptacles in the holding means 36, after which the 75

closure member 74 may be closed and locked and the newly introduced receptacles sterilized as previously disclosed.

In the above paragraphs, it has been pointed out that the sterilizing apparatus as disclosed is adapted for sterilizing receptacles or the contents thereof, and it is to be understood that the term "receptacle," as used in the specification and claims, is to be broadly construed to cover filled or unfilled receptacles.

While I have herein described and upon the drawings shown an illustrative embodiment of the invention, it is to be understood that the invention is not limited thereto but may comprehend other constructions, arrangements of parts, details and features without departing from the spirit of the invention.

I claim:

1. A receptacle holding device for a sterilizer, comprising rotatable supporting means, oppositely disposed frame members mounted thereon,

an inner and outer row of spaced members extending between said frame members, the members of said rows being substantially in radial alignment, and receptacle retaining members releasably secured to a frame member for preventing radial displacement of said receptacles.

2. In a sterilizing apparatus, the combination of a casing, a shaft mounted therein, oppositely disposed frame members mounted on said shaft, a plurality of radially spaced rows of members disposed in spaced relation extending between said frame members for holding a plurality of rows of said receptacles, a member pivoted to said frame members and engageable with each row of said receptacles for holding the same in place, and releasable locking means for securing said member in engaging relation with said receptacle and to permit movement thereof for removal of said receptacles.
